INVENTOR

EDWARD LEVY

By Attorney.

UNITED STATES PATENT OFFICE.

EDWARD LEVY, OF LONDON, ENGLAND.

SCISSORS.

1,423,127.

Specification of Letters Patent. Patented July 18, 1922.

Application filed March 16, 1920. Serial No. 366,290.

To all whom it may concern:

Be it known that I, EDWARD LEVY, a subject of the King of Great Britain and Ireland, and a resident of London, England, have invented a certain new and useful Improvement in Scissors, of which the following is a specification.

This invention has reference to improvements in or relating to scissors, and consists

- 10 in a shape and configuration of blades of the type wherein two keen cutting edges are employed. According to the present invention, the two keen cutting edges of each blade are formed in bevel fashion tangential from a half-round milled outer surface to a flat undersurface, so that in addition to the advantages of a double-edged blade, the scissors blades, when closed together, present an elliptical section of nearly round 15 rod with roughened surface for use as a butcher's steel.

In addition to the foregoing, one or a number of useful articles may be embodied in the construction of the scissors as hereininafter described to constitute an assembly or combination of useful articles, such as a knife-sharpener, can-opener, glass-cutter, screw-driver, and cork-screw, the can-opener being an adaption of the known construction with a cranked piercing pivot and cutter slidable in a T or other slot. When a glass-cutter is employed, it is found convenient to locate the same in or on a handle as before employed in combination scissors and 20 glass-cutter. It is known that combination articles have included a can-opener of the foregoing construction with a foldable corkscrew, but when such articles are included in the present improvements in scissors, it is in accordance with the appended 25 claims.

In the following description, assisted by the accompanying drawings, a practical embodiment of the said invention will be 30 described, wherein an inclusion and arrangement of all the foregoing articles is exemplified; and in said drawings:—

Figure 1 is a plan view of a detached blade member;

50 Fig. 2 is a side elevation thereof;

Fig. 3 is a plan view of a complementary blade member; and

Fig. 4 is a side elevation thereof;

Fig. 5 shows a can-opening detail hereininafter described;

55

Fig. 6 is a plan of an extended pair of scissors; and

Fig. 7 shows a corkscrew detail hereininafter described.

Like numerals of reference indicate 60 similar parts in the several views.

Reference being made to the accompanying drawings, 1 shows the blades of the scissors with their four keen cutting beveled edges 2 from the junction to the points of the blades. 65 These are of very highly tempered steel and when placed on articles, such as knives, scissors, shears and edge tools at an angle of about 30 degrees with slight pressure will sharpen same. The blades 1 are shaped 70 half-round in section and milled on the outside at 4, the said milled surface 4 being shown in Figs. 1, 3 and 6 from the junction to within half an inch of the points of the blades. The blades when held together by 75 the loops 14 and 15 of the scissors may be used as a butcher's steel. The keen cutting beveled edges 2 on the outer edges of the blades may be disposed in any desirable fashion, and bevels at an angle of about 48 degrees tangential from the half-round milling 80 4 gives good results. In Figs. 1 and 3, a flat 3 about one-eighth of an inch formed on the blade extremities is illustrated which will serve as a screw-driver, said flat 3 being preferably magnetized to give a better control 85 over small screws.

In Figs. 1, 2 and 6, a wheel 6 of steel very highly tempered and keenly edged is mounted on the loop 14 of the scissors, the 90 wheel 6 having a rotary movement and serving as a glass-cutter.

In Figs. 3, 4, 5 and 6 a can-opening construction is shown. This feature includes a steel member about half an inch in length 95 formed integral with loop 15 and rounded to a point 8, this point 8 being used for piercing the center of cans and forming a pivot. A T-shaped slot designated by the numerals 9 and 7 cut directly through the 100 shaft 16 of the scissors runs from near the junction of the scissors to the loop 15 of the scissors and accommodates the co-acting member. Fig. 5 shows this device, which comprises a beveled-edged V-shaped cutter 10 105 with an oblong shank 11 and a stop 12, and

in fitting, the stop 12 and shank 11 are passed through the T-shaped slot 7 and moves freely along the slot 9 in the shaft 16 with the cutter 10 directly below the shaft 16.

5 The adjustment of the cutter 10 may be effected by the thumb and finger placed upon the stop 12 and moved accordingly. The piercing point 8 must be pressed by the hand into the center of the can and re-
10 main inserted to give the cutter 10 the power to cut, the cutter after being adjusted being pressed by the thumb into the can in the known manner. The blades of the scissors are then held together by the hand
15 to cut the disk of the can to the right or left hand as required.

Fig. 7 shows a corkscrew 13 riveted and mounted to the shaft 17. The blades of the scissors may be fitted together by means
20 or a bolt 5 riveted over as shown.

It is obvious that the can-opener, glass-cutter, and other details may be varied in position or shape.

I claim:-

25 1. A can-opening tool of the scissors type

including a combination with the closed scissors members, the handle of one member carrying a pivoting point and having a longitudinally disposed slot with an enlargement at one end guarded by one handle member when the scissors are closed, and a cutting element movable in said slot and releasable through the slot enlargement when the handles are separated.

2. A can-opening tool of the scissors type 35 including a combination with the closed scissors members, the handle of one member carrying a pivoting point and having a substantially T-shaped slot therein, the tail portion of which is longitudinally disposed in the handle while the head portion thereof is guarded by the other handle member when the scissors are closed, and a cutting element movable in said slot and releasable from the head of the slot when the 40 handles are separated.

In testimony whereof I have affixed my signature hereto this 24th day of February 1920.

EDWARD LEVY.
